UNITED STATES PATENT OFFICE.

BURTON S. AIXMAN, OF MILWAUKEE, WISCONSIN, ASSIGNEE TO NATIONAL BRAKE & ELECTRIC COMPANY, OF MILWAUKEE, WISCONSIN, A CORPORATION OF WISCONSIN.

PUMPING SYSTEM.

1,385,068.

Specification of Letters Patent. Patented July 19, 1921.

Application filed July 27, 1917. Serial No. 183,098.

To all whom it may concern:

Be it known that I, BURTON S. AIXMAN, a citizen of the United States, residing at Milwaukee, in the county of Milwaukee and 5 State of Wisconsin, have invented a certain new and useful Improvement in Pumping Systems, of which the following is a full, clear, concise, and exact description, reference being had to the accompanying drawings, forming a part of this specification.

My invention relates to pumping systems, particularly that class commonly known as faucet controlled systems, in which the pump is submerged in the water at the bottom of 15 the well and the operation of the pump is made dependent upon opening a faucet or other outlet.

The present invention relates especially to single cylinder pumps of this class. In 20 operating single cylinder pumps I have found it advisable to use what I term an air spring or auxiliary pumping device for smoothing out the interruptions between strokes of the pump so that a steady stream 25 is discharged at the faucets or other control points.

My present invention aims to simplify the structure of a system of this class and particularly provides a simple and inexpensive 30 system in which the air spring serves the double purpose of smoothing out the inequalities in flow of the water discharged from the pump and of affording a controlling medium for operating the admission 35 and exhaust valves of the pump cylinder.

In order to acquaint those skilled in the art with the manner of constructing my invention, I shall describe the same in connection with an embodiment thereof in connection 40 with the accompanying drawings which form a part of the present specification.

Figure 1 is a diagrammatic view of a system embodying my invention;

Fig. 2 is a diagrammatic fragmentary 45 view of a modification;

Fig. 3 is a similar view of another modification;

Fig. 4 is a longitudinal vertical section of 50 the pump with parts broken away; and

Fig. 5 is a longitudinal section of the pressure controlled valve.

The system of my present invention comprises a pump cylinder 1 which is adapted to be submerged in the water at the bottom 55 of the well. A storage reservoir 2 for storing compressed air provides the pump 1

with the necessary motive fluid for its operation. The pump 1 has a water discharge pipe 3, which leads to the head of the well and is there connected to the delivery main 60 4, which leads to the consumption system, such as the pipes and faucets such as shown at 75 in Fig. 1 of a residence or the like. It is understood that the consumption system is opened only when water is desired and 65 when the consumption system is closed the pump ceases to operate. Thus the faucet control insures fresh water at all times. The well itself is the only reservoir. The discharge pipe 3 and the delivery main 4 70 are connected to an "air spring" 5 joined by the pipe 6 to the connection 7 which communicates with the pipes 3 and 4.

The air spring 5 comprises a tank adapted 75 to be partly filled with water under pressure and partly filled with air under pressure. The air is supplied from the tank 2 by way of the pipe 8 and reducing valve 9. The reducing valve 9 is in reality a spring loaded 80 check valve. The air spring 5 serves as an auxiliary pumping device for smoothing out the cessations between strokes of the pump, thereby securing a steady flow in the delivery main 4. The air which is supplied to the air spring 5 is supplied at a reduced 85 pressure to that which is supplied to the pump 1, this reduction being secured by the reducing valve 9. The reducing valve 9 may be of any preferred type as the construction of such a valve is well understood 90 by those skilled in the art. The pump cylinder 1 is supplied with compressed air by means of the pipe 10 through the valve 11. The valve 11 has a connection by way of the pipe 12 with the air spring 5 and has a connection by way of the pipe 13 with the main tank 2. The valve 11 comprises a base or frame plate 14 having a cover 15 within which the working parts of the valve are mounted. The pipe 12 which communicates 95 with the air spring 5 leads to a fluid pressure cylinder 16 having a diaphragm 17 and a piston member 18. The piston member 18 is connected by a plurality of pins 19 to a movable collar 20, which engages a main 105 spring 21 and an auxiliary spring 22. These springs are engaged at their outer ends by the collar 23, mounted on the bolt 24. The bolt 24 is secured at its inner end to the cylinder frame 25. The collar 20 is slotted to 110 receive a pin 26 mounted on the toggle lever 27. This toggle lever 27 is pivoted on the

pin 28 supported by the lug 29. A short lever arm 30 is pivoted to the end of the lever arm 27 at the pin 31. A spring shown in dotted lines is connected to the pin 34 5 mounted on the outer end of the short lever arm 30 and to the pin 28 upon which the longer arm 27 is pivoted. This spring tends to fold the two lever arms together or to collapse them. This effort of the spring is 10 transmitted to a finger 35 which when the parts are in the position shown is held just out of contact with the valve stem 36 of the movable valve 37. A stationary stop 38 is 15 mounted near the valve stem 36 in such position that the finger 35 is limited in its movement away from the valve stem 36 to obtain a reversal of the action of the spring 33.

The valve 37 controls an admission port 39 and an exhaust port 40 which communicate with the exhaust passage 41 shown in dotted lines. The central space between the ports 39 and 40 communicates by way of passage 42 with the air pipe 10 leading to the pump 1. The admission port 39 communicates with the compressed air supply pipes 13 leading to the main reservoir 2.

The pump cylinder 1 comprises a head member 44 and a foot member 45 between which the barrel 46 is fastened. The head member 44 has a socket or connection 47 to which the water discharge pipe 3 is connected. This socket or connection 47 communicates with a passageway 48, the lower end of which passageway 48 communicates with 35 the central pipe 49. The pipe 49 is fastened at its lower end to the valve cage 50 which contains the check valve 51, governing the movement of water in the discharge pipe 3. A central bolt 52 passes through the foot member 45 and is secured to the lower end of the valve cage 50, thus holding the head 44 and the foot 45 of the pump upon the end of the cylinder 46. The foot member 45 is provided with a foot valve 53 through which 45 the pump is filled after each stroke. The valve passages for the valve 53 are covered by a conical screen 54 at the lower end of the foot member 45.

The operation of the system is as follows: 50 Assuming that the tank 2 is filled with compressed air and that the exhaust port 41 is open and the admission port 39 closed after the completion of a stroke the pump 1 becomes filled with water due to the exhaust 55 ports 40 being open.

As the pressure in the tank 5 drops due to the escape of water at an outlet or faucet and as the piston 18 is moved over to the left, as shown in Fig. 5, the toggle arms 60 27-30 are moved against the spring until the spring throws the short arm 30 to the other side of center opening the admission port 39 and closing the exhaust port 40 thus admitting pressure to the pump 1. As a consequence the water is driven out of the

pump 1 through the discharge pipe, part of it going to the delivery main 4 and a part into the tank 5. The delivery main should be so proportioned that upon maximum operation of the system sufficient water will 70 be invariably discharged into the air spring for each pump stroke to raise the pressure sufficiently to operate the pressure controlled valve. This raises the pressure in the tank 5, the air being trapped in the top of the tank driving the piston 18 to the right as shown in Fig. 5 and causing the spring 33 to move the short lever arm 30 past the center so as to cause the finger 35 to engage the stem 36 of the valve 37 closing off the admission port 39 and opening the exhaust port 40. It is apparent that when the consumption system is closed as by closing all of the faucets the pressure in the tank 5 rises and shuts off the valve 37-39. This valve stays 80 closed until the faucets or other outlets are opened to reduce the pressure.

In Fig. 2 I have illustrated diagrammatically a modification of the invention in which the admission and exhaust to and 90 from the cylinder 1 is controlled by means of a cylinder and piston 56-57 which act as relay means for operating the valve 58 in the valve casing 59. This valve casing contains an admission port 60, and exhaust port 95 61 governed by the valve 58. The valve casing 59 is secured to the cylinder 56 by means of a pipe 62 which not only connects these parts together but serves as a supply pipe for air for operating the pump 1. The 100 pipe 63 leading to the cylinder 56 is in this case adapted to be connected to the valve 11 instead of the pipe 10. The pipe 64 which supplies air for operating the pump is adapted to be connected to the tank 2 as for 105 instance by connecting with the pipe 13. But when the master valve 11 operates to admit air to the pipe 63 the piston 57 is driven downward opening the admission port 60 and closing the exhaust port 61 of 110 the controlling valve 58. This admits compressed air from the tank 2 to the pump 1 by way of the short pipe 65 driving the water out at the discharge pipe 3 and raising the pressure in the tank 5 whereby the 115 valve 11 is operated.

The movable valve 58 is connected by means of a rod 66 to the piston 57 so that the movement of the piston 57 is transmitted to the valve 58.

In Fig. 3 I have illustrated diagrammatically the manner in which the master valve 11 may control a valve 67 located at the foot of the well by relay means employing compressed air.

The valve 67 is provided with an operating cylinder 68 and piston 69 for operating the movable valve element 70 which controls the port 71. The cylinder 68 has exhaust openings 72 which are adapted to be closed 120 125

off by a seat member 73 on the bottom of the piston 69. The pipe 74 which connects with the cylinder 68 is adapted to be connected to the master valve 11 instead of the pipe 10. The pipe 75 which supplies air for operating the pump 1 is adapted to be connected to the tank 2 as by way of the pipe 13. Thus when the master valve 11 admits air to the pipe 74 the plunger 69 is moved downward to cut off the exhaust passage 72 and to open the port 71 permitting compressed air from the tank 2 to move into the pump 1 for driving the water out of the main 4. This raises the pressure and as a consequence the master valve 11 operates to open the exhaust for the pipe 74 and as a consequence the piston 69 is moved upward causing the valve 70 to close off the port 71 and thus opening the exhaust port 72 for the pipe 67 of the pump 1.

It is now apparent that in the present case the single tank 5 serves both as an air spring and as a pressure sensitive element 25 for operating the master valve 11 to control the operation of the pump.

It is apparent to those skilled in the art that numerous changes and modifications may be made without departing from the 30 invention.

I claim:

1. In combination a pump cylinder, a control valve for the pump cylinder for admitting and exhausting motive fluid, a discharge pipe, means communicating with the discharge pipe for exerting a yielding pressure invariably higher than atmosphere upon the fluid in the same, a source of motive fluid and a pressure controlled valve subject 40 to the change of pressure caused in the discharge main by the individual pump strokes governing the shifting of the control valve for each stroke of the pump.

2. In combination a pump cylinder adapted to be submerged in the water in the well, a discharge pipe, means communicating with the discharge pipe for exerting a yielding pressure invariably higher than atmosphere upon the liquid in the same, a source of compressed air and a valve controlled by the pressure in the discharge main for admitting compressed air to and exhausting air from the pump cylinder to cause the same to operate.

3. In combination a pump, a source of motive fluid, a yielding pressure accumulator, said accumulator maintaining a pressure invariably above atmosphere, said accumulator being responsive to the individual pump strokes and pressure controlled means connected to said accumulator and responsive to the individual pump strokes controlling the admission of motive fluid to the pump.

4. In combination a pump cylinder, a source of compressed air, an air chamber,

said chamber invariably having a pressure higher than atmosphere, a discharge pipe between the pump and air chamber, a valve between the source of compressed air and the pump, and means responsive to the variations of pressure in the air chamber caused by the strokes of the pump for controlling said valve.

5. In combination, a source of compressed air, a pump cylinder, an air spring connected to the pump cylinder, said air spring being connected to said compressed air tank, a controlling valve in said connection, a connection between the compressed air tank and the pump cylinder, and a valve responsive to the variations in pressure in the air spring due to the pump stroke for governing the admission and exhaust of compressed air to and from the pump cylinder.

6. In combination, a compressed air tank, an air spring, a pump cylinder adapted to be submerged in the water at the bottom of the well, a discharge pipe connecting the pump cylinder and the air spring, a pressure responsive element subject to the variations of pressure due to the pump strokes, a master valve controlled by said pressure responsive element, an operating element controlled by said valve and a control valve for admitting air to and exhausting air from the pump cylinder, said valve being actuated by said operating element.

7. In combination, a pump cylinder adapted to be submerged in the water at the bottom of the well, a tank for compressed air, an air spring, a discharge pipe connecting the pump and the air spring, and a pressure responsive element communicating with the air spring and responsive to the individual strokes of the pump, valve means at the head of the well controlled by said pressure responsive element, valve means at the foot of the well and relay means controlled by the valve at the head of the well for operating the valve at the foot of the well for controlling the admission and exhaust to and from the pump cylinder.

8. In combination, a pump cylinder, a source of compressed air, an air chamber, a discharge pipe between the pump and the air chamber, a valve between the source of compressed air and the pump, means responsive to the variations of pressure in the air chamber caused by the strokes of the pump for controlling the valve, and a normally closed faucet controlled system communicating with the discharge pipe.

9. In combination, a pump adapted to be submerged in the liquid to be pumped, a source of motive fluid, a yielding pressure accumulator connected to the discharge of the pump, said accumulator being responsive to the individual pump strokes, pressure controlled means connected to said accumulator and responsive to the individual pump strokes.

- controlling the admission of motive fluid to the pump and a normally closed faucet control system communicating with the pressure accumulator and the discharge of the 5 pump.
10. In combination, a pump cylinder adapted to be submerged in the water in the well, a discharge pipe, means communicating with the discharge pipe for exerting a 10 yielding pressure upon the liquid in the same, a normally closed faucet control distributing system communicating with the discharge pipe, a source of compressed air and a valve controlled by the pressure in 15 the discharge main for admitting compressed air to and exhausting air from the pump cylinder to operate the same.
11. In combination, a pump, a source of compressed air, a pressure trap, means connecting the source of compressed air and the trap for charging the trap with air under 20 suitable pressure, a pump discharge pipe connecting the pump and the trap, a distribution pipe communicating with the discharge 25 pipe, said distribution pipe having normally closed faucet control outlets, and a pressure controlled valve governed by the variations in pressure in the trap for governing the individual strokes of the pump.
- 30 12. In a faucet control system, the combination of a pump, a source of motive fluid, a pressure trap, a discharge pipe connecting the pump to the trap, a faucet controlled delivery system in communication 35 with the delivery pipe of the pump, a valve device for controlling the admission of the motive fluid to and from the pump, and a pressure element governed by the variations of pressure in the trap for operating the 40 valve device.
13. In a faucet control system, the combination of a single cylinder pump having a discharge pipe, a faucet control delivery system normally under pressure, an air 45 spring for smoothing out the pressure in the system over the intervals between the strokes of the pump, and a pressure controlled valve controlled by the variations in pressure in said discharge pipe governing 50 the admission and exhaust of motive fluid to and from the pump.
14. In combination, a pump, a source of motive fluid, said pump having a discharge pipe invariably discharging a solid stream 55 of the liquid to be pumped, a trap connected to the discharge pipe, a distribution main communicating with the discharge pipe invariably below the level of liquid in the trap, and a pressure controlled valve governed by the variations in pressure in the 60 trap for controlling admission and exhaust of the pump.
15. In combination, a pump adapted to be submerged in the water in the well, a source 65 of motive fluid serving as the sole operating means for actuating said pump, a yielding pressure accumulator, said accumulator being responsive to the individual pump strokes and pressure controlled means connected to said accumulator and responsive to the individual pump strokes, controlling the application of said motive fluid to the pump at each stroke.
16. In combination, a pump adapted to be submerged in the liquid to be pumped, a source of motive fluid under pressure serving as the sole actuating means for operating said pump, a yielding pressure accumulator maintaining a pressure invariably above atmosphere, said accumulator being responsive to the individual pump strokes, and pressure controlled means connected to said accumulator and responsive to the individual pump strokes controlling the exhaust of motive fluid from the pump at each stroke.
17. In a system of the class described, a pump, a source of compressed air, an air spring connected to the discharge of the pump, a normally closed faucet control system communicating with the discharge of the pump, a control valve for the pump, said control valve having a plurality of ports comprising a live air port and an exhaust port and a valve member adapted to cover either the live air port or the exhaust port, a pressure sensitive element controlling the position of the valve, said element having a snap action for throwing the valve with a quick motion and being subject to the pressure conditions prevailing within the air spring.
18. In combination, a pump, a source of motive fluid, a pressure accumulator, a pressure sensitive element subject to the variations of pressure in said accumulator, a master valve controlled by said pressure sensitive element, a motor element and a relay valve governing the individual working strokes of the pump.
19. In combination, a pump, a source of motive fluid, a pressure accumulator connected to the discharge side of the pump, a normally closed faucet control system communicating with the discharge side of the pump and a pressure sensitive element subject to the variations in pressure in said accumulator for controlling the effective application of motive fluid to the pump for each stroke thereof.
20. In combination, a pump, a source of motive fluid, a main valve governing the admission of motive fluid to and from the pump, a normally closed pressure distributing system and pressure sensitive means directly responsive to the pressure of the liquid discharged from the pump into the closed system for controlling the individual strokes of the pump caused by said main valve, said pressure sensitive element cutting

- off pressure from the pump when the pressure rises above a predetermined amount and maintaining said position until the pressure drops a predetermined amount.
- 5 21. In combination, a pump cylinder adapted to be submerged in the water to be pumped, a tank for compressed air, a steady flow chamber, a discharge pipe connecting the pump and the auxiliary device, and a pressure responsive element communicating with the steady flow chamber and responsive to the individual strokes of the pump, valve means at the head of the well controlled by said pressure responsive element, valve means at the foot of the well and relay means controlled by the valve at the head of the well for operating the valve at the foot of the well for controlling the admission and exhaust to and from the pump cylinder.
- 10 22. In a faucet controlled system, the combination of a source of motive fluid under pressure, a pump, a main valve governing the admission of motive fluid to and from the pump and governing the individual strokes of said pump, a normally closed pressure distributing system, and pressure sensitive means governed by the pressure of the liquid discharged from the pump into the system, said means actuating the main valve upon a predetermined rise in pressure in the system for cutting off the supply of motive fluid and maintaining the same so cut off until a predetermined drop in pressure in
- the system occurs whereupon motive fluid is again admitted to the pump.
- 35 23. In combination, a pumping chamber adapted to be submerged in the liquid to be pumped, a source of motive fluid for said pumping chamber, an air spring for supplying the flow of liquid between strokes of the pump to the discharge system, a discharge main communicating with the pump and with the air spring and connected to a distributing system maintained under pressure, and a pressure sensitive element subject to the raising of pressure in the discharge main for permitting the exhaust of motive fluid from the pump.
24. In combination, a pumping chamber adapted to be submerged in the liquid to be pumped, and to be filled by submergence pressure, a source of motive fluid for driving the liquid from said pumping chamber, a discharge main, a distributing system maintained under pressure connected to said discharge main; a pressure sensitive element subject to the pressure in the discharge main, and a valve controlled by said pressure sensitive element governing the effective application of the motive fluid to the liquid in the pumping chamber for each stroke of the pump.
- 50 55 60
- In witness whereof I hereunto subscribe my name this 20th day of July, A. D. 1917.

BURTON S. AIKMAN.
